The ornamental design for a battery enclosure, as shown and described.

DESCRIPTION

FIG. 1 is an isometric view of a top, left, and front side of an ornamental design for a battery enclosure;

FIG. 2 is a front elevational view of the battery enclosure of FIG. 1;

FIG. 3 is a rear elevational view of the battery enclosure of FIG. 1;

FIG. 4 is a left side elevational view of the battery enclosure of FIG. 1;

FIG. 5 is a top plan view of the battery enclosure of FIG. 1; and,

FIG. 6 is a bottom plan view of the battery enclosure of FIG. 1.

The dash-dash-dash broken lines are included for the purpose of illustrating portions of the battery enclosure that form no part of the claimed design. Further, the dash-dot-dash-dot broken lines define boundaries of the claimed design and form no part of the claimed design.
